FAUCET DRINKING ATTACHMENT

John Bishop, Centerline, Mich.

Application November 4, 1950, Serial No. 194,080

5 Claims. (Cl. 299—11)

1

My invention relates to a new and useful improvement in a faucet drinking attachment adapted for mounting on a water faucet and movable to operative and inoperative position and so constructed that when moved to operative position, the attachment will divert a portion of the water into a stream accessible to a person for drinking.

It is an object of the present invention to provide a drinking attachment of this class which will be simple in structure, economical of manufacture, durable, compact, easily and quickly installed, easily operated and highly efficient in use.

Another object of the invention is the provision of an attachment of this class so constructed and arranged that it will retain its position when moved either to operative or inoperative position.

Other objects will appear hereinafter.

It is recognized that various modifications and changes may be made in the detail of structure illustrated without departing from the invention and it is intended that the present disclosure is to be considered but the preferred embodiment.

Forming a part of this application are drawings, in which,

Fig. 1 is a central sectional view of the invention showing it applied and in operative position,

Fig. 2 is a sectional view similar to Fig. 1 showing the attachment in inoperative position,

Fig. 3 is a sectional view taken on line 3—3 of Fig. 2,

Fig. 4 is a sectional view taken on line 4—4 of Fig. 2,

Fig. 5 is an elevational view taken on line 5—5 of Fig. 2.

In the drawings I have illustrated the invention used with a faucet having a spout 9. The invention comprises a body 10 cut away at one face to provide, at the upper end, the arcuate arms 11 and the notch 12. Formed at the lower end is a trough 13 which communicates with the passage 14 extending upwardly from the trough. Formed in the body is a longitudinally or vertically directed groove 15 in which is adapted to engage one leg 16 of a U-shaped spring, this leg being pivoted at its end on the pin 17. The other leg 18 is provided with the angularly turned portion 19.

In use this U-shaped member which may be termed a spring clip, is inserted into the open end of the faucet, the angularly turned portion 19 facilitating the insertion of the clip into the

2

faucet. It is preferred that this spring clip be inserted far enough into the faucet so that the bite 20 of the clip will engage the end edge of the spout 9 when the structure is in inoperative position as shown in Fig. 2. When mounted as in Fig. 2, the flow of water through the spout will be ordinary as the attachment will not materially interfere with the flow of water. When it is desired to use the device the body 10 is swung outwardly at its upper end or inwardly at its lower end so as to swing on the pivot 17. As the body 10 swings inwardly at its lower end, the inclined edge 21 of the sides of the trough 13 will engage the end edge of the faucet spout 9 so that the body moves into the position shown in Fig. 1. When in this position a part of the water 22 will flow into the trough to provide a stream 23 passing through the passage 14 and flowing outwardly from the spout at an angle 20 as indicated in Fig. 1. This movement from the position shown in Fig. 2 to the position shown in Fig. 1 is an easy and quick one and as the inclined edges 21 of the walls of the trough ride over the end edge of the spout 9, the spring clip 25 will move bodily downwardly toward the end of the spout so that the angularly turned portion 19 will lie in engagement throughout its full length with the inner surface of the faucet spout. When moved from the position shown in Fig. 1 to the position shown in Fig. 2 the operator will unconsciously move the structure upwardly so that the bite 20 is engaged by the end edge of the spout 9 as shown in Fig. 2 and the spring clip will engage the inner surface only at the bend between the parts 18 and 19. This facilitates the movement of the attachment from inoperative to operative position. It will be noted that when in operative position the body is in engagement with the spout at the inclined edges 21 and also at the end edges of the arms 11 while the portion 19 is in full engagement with the inner surface of the spout. This affords a very rigid mounting when the attachment is in use so that disarrangement of the same on the spout is avoided and a highly efficient drinking attachment is thus provided.

What I claim is:

1. A drinking attachment adapted for a faucet spout, comprising: a body having a passage formed therein and opening through the upper end thereof; a U-shaped spring clip pivotally mounted at one end of one leg to said body the end of the other leg being projectible into the interior of said spout, said other leg having an angularly turned terminal portion, said body be-

ing swingable inwardly of said spout to operative position and outwardly of said spout to inoperative position, said clip engaging at the juncture between the terminal portion of said other leg and the main body of said other leg with the inner surface of said spout by the movement of said body to inoperative position and said terminal portion engaging throughout its length with the inner surface of said spout upon movement of said body to operative position.

2. A drinking attachment adapted for a faucet spout, comprising: a body having a passage formed therein and opening through the upper end thereof; a U-shaped spring clip pivotally mounted at one end of one leg to said body and the other leg being projectible into the interior of said spout, said other leg having an angularly turned terminal portion, said body being swingable inwardly of said spout to operative position and outwardly of said spout to inoperative position, said clip engaging at the juncture between the terminal portion of said other leg and the main body of said other leg with the inner surface of said spout upon movement of said body to inoperative position and said terminal portion engaging throughout its length with the inner surface of said spout upon movement of said body to operative position; and a trough on the lower end of said body communicating with the lower end of said passage and adapted, upon swinging of said body inwardly of said spout to operative position, for receiving liquid passing through said spout and conducting the same to said passage.

3. A drinking attachment adapted for a faucet spout, comprising: a body having a passage formed therein and opening through the upper end thereof; a U-shaped spring clip pivotally mounted at one end of one leg to said body and the other leg being projectible into the interior of said spout, said other leg having an angularly turned terminal portion, said body being swingable inwardly of said spout to operative position and outwardly of said spout to inoperative position, said clip engaging at the juncture between the terminal portion of said other leg and the main body of said other leg with the inner surface of said spout by the movement of said body to inoperative position and said terminal portion engaging throughout its length with the inner surface of said spout upon movement of said body to operative position; and a trough on the lower end of said body communicating with the lower end of said passage and adapted, upon swinging of said body inwardly of said spout to operative position, for receiving liquid passing through said spout and conducting the same to said passage, said trough having oppositely disposed walls each provided with an inclined edge adapted for engaging and riding over the end edge of the spout upon movement of said body to operative and inoperative position.

4. A drinking attachment adapted for a faucet spout, comprising: a body having a passage formed therein and opening through the upper end thereof; a U-shaped spring clip pivotally mounted at one end of one leg to said body and the other leg being projectible into the interior of said spout, said other leg having an angularly

turned terminal portion, said body being swingable inwardly of said spout to operative position and outwardly of said spout to inoperative position, said clip engaging at the juncture between the terminal portion of said other leg and the main body of said other leg with the inner surface of said spout by the movement of said body to inoperative position and said terminal portion engaging throughout its length with the inner surface of said spout upon movement of said body to operative position, and a trough on the lower end of said body communicating with the lower end of said passage and adapted, upon swinging of said body inwardly of said spout to operative position, for receiving liquid passing through said spout and conducting the same to said passage; said trough having oppositely disposed walls each provided with an inclined edge adapted for engaging and riding over the end edge of the spout upon movement of said body to operative and inoperative position; and a pair of spaced apart arms on said body engaging the periphery of said spout upon movement of said body from inoperative to operative position.

5. A drinking attachment adapted for fastening to a faucet spout, comprising: a body having a passage formed therein and opening through the upper end thereof; a U-shaped spring clip pivotally mounted at one end of one leg to said body and the other leg being projectible into the interior of said spout, said other leg having an angularly turned terminal portion, said body being swingable inwardly of said spout to operative position and outwardly of said spout to inoperative position, said clip engaging at the juncture between the terminal portion of said other leg and the main body of said other leg with the inner surface of said spout by the movement of said body to inoperative position and said terminal portion engaging throughout its length with the inner surface of said spout upon movement of said body to operative position, and the leg pivoted to said body extending parallel to the axis of said passage and in engagement with the surface of said body; and a trough on the lower end of said body communicating with the lower end of said passage and adapted, upon swinging of said body inwardly of said spout to operative position, for receiving liquid passing through said spout and conducting the same to said passage; said trough having oppositely disposed walls each provided with an inclined edge adapted for engaging and riding over the end edge of the spout upon movement of said body to operative and inoperative position; and a pair of spaced apart arms on said body engaging the periphery of said spout upon movement of said body from inoperative to operative position.
